UNITED STATES PATENT OFFICE

123,459

DESIGN FOR A DRESS

Christine Mazola, New York, N. Y.

Application September 25, 1940, Serial No. 95,366

Term of patent 3½ years

To all whom it may concern:

Be it known that I, Christine Mazola, a citizen of the United States and a resident of the city of New York, in the county of New York and State of New York, have invented a new, original, and ornamental Design for a Dress, of which the following is a specification, reference being had to the accompanying drawing forming a part thereof.

Fig. 1 is a front view of a dress showing my new design.

Fig. 2 is a rear view of the dress shown in Fig. 1.

I claim:

The ornamental design for a dress, substantially as shown.

CHRISTINE MAZOLA.
